UNITED STATES PATENT OFFICE

JACQUES BIENENFELD, OF PARIS, FRANCE

MULTIPLE DISCONNECTIBLE CLASP CHIEFLY FOR NECKLACES AND THE LIKE
PIECES OF JEWELRY

Application filed September 27, 1929, Serial No. 395,550, and in France October 5, 1928.

A known article of jewelry consists of a unit comprising a plurality of necklaces, "ropes" so-called, of pearls, precious stones and the like of equal or different lengths. Heretofore the several elements, that is, the individual necklaces or ropes, of the units were fastened together and interconnected by a single clasp the size of which was interchangeable and depended on the number of elements forming the unit.

My invention allows a certain number of different jewels to be obtained with the elements forming a single jewel, each of said different jewels being constituted either by one of the elementary strings or chains used alone, or by any arrangement of two or more of these elementary jewels.

The object of my invention is a clasp composed of a number of separable or elementary clasps, so constructed that one of the separable or elementary clasps may be used separately to serve as a connecting means for a single necklace or rope or a double necklace or rope, or the single clasps may be assembled together to serve as connecting means for a larger number of necklaces or ropes.

Another object of my invention resides in the different forms of execution and in the means for securing the individual clasps together. In particular the complete or compound clasp may comprise individual clasps showing at each end the usual means for hooking on one or more jewel strings or rows, these means comprising yielding spring catches. Means are also provided for detachably engaging adjacent individual clasps. For this purpose one of a pair of individual clasps is provided with a yielding spring catch controlled by thumb-pieces and adapted to enter a registering recess in the other individual clasp of the pair. The last mentioned individual clasp is on the other hand provided with projections or dowels adapted to enter recesses in the first mentioned individual clasp whereby the assembly is made very rigid.

My invention further comprises further additional means for maintaining rigidity of the assembly of individual clasps, said means comprising a spring inserted between two

adjacent parts, for instance in the recess in one part and adapted to exert a thrust against the dowel projecting from the other part so as to urge the individual clasps apart as soon as the catch or the like connecting them is 55 suitably released.

I have shown in appended drawings and described hereinbelow by way of example, two forms of execution of my invention:

Fig. 1 shows the inner side of a compound 60 clasp according to my invention.

Fig. 2 is a side view thereof.

Fig. 3 is a vertical cross-section thereof along line B—B of Fig. 2 with the parts disengaged. 65

Fig. 4 is a cross-section along line A—A of Fig. 1 with the parts disengaged.

Fig. 5 shows a modification in the clasp comprising means for automatically separating the elementary clasps. 70

Fig. 6 is an end view of the individual clasp shown in the lower part of Fig. 5.

Referring to the drawings, the compound clasp comprises, as explained, a plurality of 75 separate disconnectible clasps 1, 2 adapted to be connected together and disconnected one from the other as desired.

Each part 1, 2 comprises an individual clasp body with its usual necklace securing means such as rings 3 and catches 5—6, said 80 rings 3 adapted to receive the ends of the necklaces, ropes or the like, said rings being either single as for part 1 or double or multiple as for part 2 (Fig. 3).

The parts 1 and 2 are adapted to be disposed one against the other and engaged with and disengaged from one another; in view of this, one of the parts 2 for instance has a spring catch comprising a hook 7 carried by a blade 8, provided with a thumb-piece 9 (Fig. 4) and projecting beyond one of the sides 10 of the clasp. The individual clasp 1 shows on its side 11 adapted to contact with the side 10 of the clasp 2, an aperture 12, the edge of which is adapted to be engaged by 95 the hook 7, thus serving as an anchorage for the same. The part 1 is also provided on each side of the said recess with dowels 13, 14 positioned to enter corresponding recesses 15, 16 provided in part 2 perpendicularly to its side 100

or face 10. Since the hook is spring pressed by the blade 8 and sliding movement as between the clasp bodies 1 and 2 is prevented by the engagement of the dowels 13 and 14 with the recesses 15 and 16, the two clasp bodies may be firmly locked together.

In the modification illustrated in Fig. 5 the individual clasps are locked one to the other by means of a hook 17 controlled by the thumb-piece 18. In this instance the hook is mounted on a spring blade 18a which is adapted to flex in a direction parallel to the surface of the part which carries it, or in other words in a direction at right angles to that of the hook and blade of the previous figure. The device of this figure is also provided with automatic disconnecting means comprising a spring 19 disposed in one of the recesses 15, 16 and compressed by a piston 19a when the two parts 1, 2 are locked together by the dowels 13 and 14 and the engagement of the hook 17. The spring 19 urges the dowel 14 out of the recess 19a as soon as the hook 17 is released whereby the parts 1, 2 are automatically separated.

The working of my improved clasp is as follows: It is sufficient to engage the dowels 13, 14 in their recesses 15, 16 respectively to cause the hooks 7 or 17 to snap into engagement with the edges of the recesses in part 1. Conversely by pressing on the thumb-piece or the like provided on the hook, part 1 may be released from the said hook whereby the individual clasps together with the necklaces or ropes connected with them respectively are separated from each other.

The above forms of execution are obviously given only by way of example, the shape, material and size of the component parts and the detail arrangements being liable to change within the scope of the appended claims.

What I claim is:

1. A compound clasp for use in fastening a variable number of necklaces, said compound clasp comprising a pair of individual clasps disposed side by side, means for engaging the individual clasps with each other in the side by side position, and for disengaging them from each other, said means comprising a yielding hook mounted on one of said individual clasps and an anchorage for the hook on the other of said individual clasps, one of said individual clasps being provided with recesses in the side adapted to contact with the other individual clasp, the said other individual clasp being provided with dowels adapted to enter the said recesses.

2. Means for connecting the ends of a variable number of necklaces comprising a compound clasp consisting of a pair of individual clasps retained in contiguity side by side by releasable locking means, each of said individual clasps being provided with means to which an end of a necklace may be secured,

together with means detachably connected with each of said individual clasps, to each of which means an end of a necklace may be secured.

In testimony whereof I affix my signature. 70
JACQUES BIENENFELD.
